Attns.

UNITED STATES PATENT OFFICE.

HANS HANSEN, OF ROCK ISLAND, ILLINOIS.

WEDGE-PARALLEL.

1,285,139.

Specification of Letters Patent. Patented Nov. 19, 1918.

Application filed January 2, 1918. Serial No. 210,100.

To all whom it may concern:

Be it known that I, HANS HANSEN, a citizen of the United States, residing at Rock Island, in the county of Rock Island and State of Illinois, have invented a certain new and useful Improvement in Wedge-Parallels, of which the following is a full, clear, concise, and exact description, reference being had to the accompanying drawings, forming a part of this specification.

This invention relates to improvements in wedge parallels.

In Patent No. 833,598 issued to me October 16, 1906 for improvement in gage, is shown and described a wedge parallel such as is adapted for use by machinists in connection with milling, planing and other machine operations where it is necessary to accurately determine the height of the work being operated upon at different points. The essential of such a gage or wedge parallel of course resides in the fact that the upper and lower gaging edges or surfaces must be maintained in absolute parallelism in all adjusted positions of the wedge elements.

In the structure described in said Patent No. 833,598, certain objectionable features have been discovered and among them may be mentioned the facts that a screw-driver or other tool is necessary in setting or adjusting the gage and in the actual manufacture, great difficulty is experienced in machining the parts so as to obtain the requisite constant parallelism of the gaging edges. The latter difficulty is due to the fact that in the structure as shown in said patent, it is necessary to maintain substantially absolute parallelism between all of the engaging surfaces of the two wedge elements including those of the tongue and groove connection.

The object of the present invention is to provide a gage or wedge parallel which may be readily adjusted without the use of any screw-driver or other tool and which will entail a much less manufacturing cost with increased certainty of the requisite accuracy.

In the drawing forming a part of this specification, Figure 1 is a longitudinal, sectional view of a gage or wedge parallel embodying my improvements. Fig. 2 is a top plan view of the device as illustrated in Fig. 1. Fig. 3 is an enlarged, vertical, sectional view, taken substantially on the line 3-3 of

Fig. 1. Fig. 4 is a detail perspective of one of the retaining parts employed with my improvements. And Fig. 5 is a similar view of one of the steel spring uniting means. 60

In said drawings, duplicate, substantially right-angle triangular wedge elements 10-10 are shown, each of said wedge elements having a gage surface or edge 11 and an inclined edge 12. As shown in the drawing, the wedge elements 10-10 may be made in the form of castings and suitably cut away, as indicated at 13-13 to lessen the weight and reduce the amount of material required. 65

Each wedge element 10, on its inclined edge is provided with a comparatively deep longitudinally extending groove or recess 14 which extends from end to end. At a point intermediate the top and bottom of said groove 14, the sides thereof are undercut, as indicated at 15-15. Seated in the bottom of each of said grooves 14 and rigidly held in place therein by a set-screw 16, is an elongated plate 17 having upturned ends 18-18 70 for the purpose hereinafter described, it being observed that each plate 17 equals substantially the length of the groove in which it is seated. 75

Interposed between the wedge elements 85 10-10 are a pair of spring plates, designated generally by the reference A. Each of said plates A consists of a spring steel plate bent into U-shape so as to provide parallel arms 19 and 20, the width of the latter, 90 throughout their greater length, being such as to permit the same to be seated within the grooves 14-14. At their free ends, each of the arms 19 and 20 is provided with laterally extended flanges 21-21, the latter being adapted to slide within the undercut portions 15-15 of the grooves 14. Each of the elements A is so made that when the same is applied to the wedge elements, there will be an inherent spring tension con- 100 stantly tending to bring the enlarged or free ends toward each other. Two of said elements A are preferably employed, the same being oppositely arranged, as indicated in Fig. 1. 105

From the preceding description, it will be seen that when all of the parts are assembled, the two elements A will effectively and constantly draw the two wedge elements into close contact with each other on their 110 inclined edges or surfaces 12. At the same time, relative longitudinal movement of the

wedge elements is permitted, the members A—A sliding with respect to the wedge elements and the sliding movement of the wedge elements being limited when the two members A—A are engaged with the stops or flanged ends 18—18. Furthermore, due to the fit of the main portions 19 and 20 of each member A in the grooves 14—14, relative lateral shifting of the wedge elements 10 is positively prevented.

With the arrangement herein shown and described, it is apparent that the requisite parallelism of the gaging surfaces or edges will be obtained by merely insuring true flat or plain surfaces 12—12, since it is immaterial, in obtaining said parallelism, whether the grooves 14 are absolutely accurate or not. It is evident that if the surfaces 12—12 are true plain surfaces, the spring-acting members A—A will maintain the wedge elements in constant and proper contact to insure the parallelism of the gaging edges necessary and furthermore, the wedge elements may be adjusted as desired without the use of any tool since it is only necessary to overcome the comparatively slight friction due to the sliding of the members A—A relatively to the wedge elements 10—10.

The device herein shown and described 30 presents an exceedingly simple and comparatively cheap manufacturing proposition with increased certainty of the requisite accuracy in addition to the fact that the adjustments may be effected by the user with a minimum of effort. It will be observed also that there are no projecting parts such as would be liable to be broken or damaged or be caught in the clothing of the user.

I claim:

40 1. The combination with two members relatively slidable and having flat engaging edges, of inherently resilient means slidably connecting said members and holding them in close edge to edge contact with each other, said means being seated partly within the engaging edge of one of said members and partly within the engaging edge of the other of said members.

2. The combination with two members 50 relatively slidable and having flat engaging services, of inherently resilient means slidably connecting said members and holding them in close contact with each other, said means including a U-shaped spring plate, the free ends thereof being attached to the said members.

3. In a device of the character described, the combination with wedge sections, each of approximately right-angle triangular 60 form, the inclined edge of each section having a longitudinally extending groove there-

in, of means having portions thereof seated in each of said grooves and extending between said sections to hold them in close contact with each other on their inclined edges, said means permitting relative sliding movement between said sections. 65

4. In a device of the character described, the combination with two wedge sections, each of approximately right-angle triangular form and having their inclined edges in sliding engagement, of resilient means for holding said sections in close contact, said means being disposed entirely within the side planes of said sections and extending from one section to the other across said edges. 70

5. In a device of the character described, the combination with two wedge sections with inclined engaging flat edges, each of 75 said edges being provided with a longitudinally extending groove, of spring means having portions thereof seated in said grooves and slidably associated with both wedge sections, and means limiting the relative sliding movement of said sections. 85

6. In a device of the character described, the combination with two wedge sections of approximately right-angle triangular form, the inclined edges of said sections being flat 90 and in sliding contact with each other, each of said edges having a longitudinally extending undercut groove therein, of a spring plate mounted within said grooves and having portions thereof engaging in the undercut portions of said grooves, said spring plate being slidable with respect to said wedge sections and preventing relative lateral movement therebetween. 95

7. In a device of the character described, 100 the combination with two wedge sections, each of approximately right-angle triangular form, the inclined edges of the sections having longitudinally extending grooves therein, portions of said grooves being undercut, of limiting stops at the ends of said grooves, and a pair of spring plates mounted in said grooves, each of said spring plates being of U-shape with the free ends thereof enlarged and adapted to engage in the undercut portions of said groove, the main portions of said U-shaped spring plates corresponding in width to the width of said grooves to thereby prevent lateral movement between said sections. 110 105 115

In witness that I claim the foregoing I have hereunto subscribed my name this 8th day of December 1917.

HANS HANSEN.
